UNITED STATES PATENT OFFICE

118,095

DESIGN FOR A DRESS

Katheryn Rost, New York, N. Y.

Application October 20, 1939, Serial No. 87,745

Term of patent 3½ years

To all whom it may concern:

Be it known that I, Katheryn Rost, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific sleeve members which are tucked as shown, in association with Shirred shoulders and a narrow row of matching tucking on each side of the blouse.

I claim:

The ornamental design for a dress, substantially as shown and described.

KATHERYN ROST,
